UNITED STATES PATENT OFFICE.

CHARLES E. ERICKSON, OF LAREDO, TEXAS.

PENCIL HOLDER.

1,407,738.

Specification of Letters Patent. Patented Feb. 28, 1922.

Application filed May 26, 1919. Serial No. 299,868.

To all whom it may concern:

Be it known that I, CHARLES E. ERICKSON, a citizen of the United States, residing at Laredo, in the county of Webb and State 5 of Texas, have invented certain new and useful Improvements in Pencil Holders, of which the following is a specification.

This invention relates to holders for supporting a plurality of pencils, and other 10 scribes in angular spaced relation, being particularly adapted for use by draftsmen in laying out artistic lettering, monograms, or the like.

In engraving on precious metals, the design 15 to be engraved or cut upon the metal is first laid out, thereon, preferably by lead pencil and it is a comparatively tedious and expensive, time absorbing operation to lay out monograms or designs with a single pencil, difficulty being experienced in 20 properly spacing lines of the letter, particularly when letters of the old English type are used; and it is an object of this invention to provide a holder for containing or 25 carrying a pair of pencils or other scribes in such manner that the distances between the points of the pencils or scribes may be varied to regulate the distance between the lines in the design and which will materially 30 facilitate the making of designs, in that two lines may be marked at the same time and properly spaced.

More specifically an object of the invention 35 is to provide a holder as specified which comprises a pair of scribe carrying tubes disposed in angular relation to each other and connected by a rigid saddle or bracing member which has substantially cylindrical saddles upon its ends for firm 40 connection with the scribe carrying tubes to form a rigid and secure holder for the scribes, and further to split the said tubes at their outermost portions to adapt them for fitting scribes of varying diameters.

45 Other objects of the invention will appear from the following detailed description taken in connection with the accompanying drawing, forming a part of this specification and in which drawing:

50 Figure 1 is a perspective view illustrating the tube of the scribe holder.

Figure 2 is a sectional view through the

holder and through a pair of pencils carried thereby, and

Figure 3 is a side elevation of the holder 55 showing pens therein.

Referring more particularly to the drawing, the holder, for the pencils or analogous scribes comprises a pair of cylindrical tubes 5 and 6 formed of sheet metal of sufficient resiliency to permit them to maintain the frictional grip upon the pencils or other scribes to prevent longitudinal movement of the pencils during the operation thereof. These tubes 5 and 6 are split longitudinally 60 at their outermost portions as shown at 7 to permit yieldable frictional engagement thereof with the pencils and also to permit the adjustment of the diameter of the tube by either squeezing the edges along 65 the slots together to grip smaller pencils or spreading them farther apart to permit the insertion of larger pencils or scribes. The ends of the tubes 5 and 6 are 70 preferably rolled as shown at 8, to prevent 75 the formation of sharp edges at their ends which would have a tendency to cut or gouge into the pencil during the mounting thereof in the tube, as well as preventing the formation of sharp edges or 80 corners which might injure the fingers of the user and also to serve as a reinforcement for and to prevent the deformation of the 85 said tubes.

The tubes 5 and 6 are connected by a brace 90 structure 9 which comprises a flat intermediate portion 10 having substantially semi-cylindrical saddles 11 and 12 upon its opposite ends which engage the outer surfaces of the tubes 5 and 6 respectively at their innermost 95 portions and are attached thereto in any suitable manner such as by solder. If it is so desired the bracing structure 9 may be formed of two plates 13 and 14, as shown in Figure 2 of the drawings, these plates 95 having their flat intermediate portions soldered one to the other, to form the connecting bracing structure 10, each of which plates has one half of the saddle structures 11 and 12 formed upon its opposite ends. 100 The tubes 5 and 6 are both disposed at the same angle radiating from the common center of their axis and bisecting the connecting bracing structure 10 so that the long pencil

or scribe A may be inserted through either of the tubes while the short pencil or scribe B is carried by the other tube. In Figure 3 of the drawings, pen holders C and D are shown carried by the holder, and it is to be understood that pencils, pens or any other desired type of scribe may be used in connection with the holder without departing from the spirit of this invention.

10 From the foregoing description taken in connection with the accompanying drawing, it will be apparent that a holder has been provided which will rigidly and securely hold a pair of scribes in angular adjusted relation with respect to each other, one which will not give or spring, consequently impairing the positioning, during use, and it is to be understood that changes in details may be made without departing from the 20 spirit of the invention, but;

I claim:

1. A scribe holder comprising a pair of sleeves disposed in angular relation and split at their relative outermost portions, each of 25 said sleeves being provided with a reinforcing, protecting bead, a bracing member at-

tached to and connecting said sleeves, said bracing member comprising an intermediate portion having substantially semi-cylindrical saddles formed upon its ends and rigidly 30 attached to said sleeves.

2. A scribe holder comprising a pair of sleeves disposed in angular relation and split at their relative outermost portions, each of 35 said sleeves having its ends rolled to form reinforcing, protecting beads, a bracing member attached to and connecting said sleeves, said bracing member comprising a pair of plates having their intermediate portions rigidly connected and their end portions shaped for co-action to form substantially semi-cylindrical saddles, said saddles being rigidly attached to said sleeves.

3. A scribe holder comprising a pair of longitudinally split sleeves, and a bracing 45 member including an intermediate portion having substantially semi-cylindrical saddles formed upon its lateral edges and converging toward each other, said saddles adapted for rigidly receiving said sleeves in 50 intermediate the split portions thereof.

CHARLES E. ERICKSON.
